(57) **CLAIM**

The ornamental design for a manifold for selectively dispersing multiple fluid streams, as shown and described.

DESCRIPTION

FIG. 1 is a perspective view of a manifold for selectively dispersing multiple fluid streams, the broken lines showing environment for illustrative purposes only and forming no part of the claimed design;

FIG. 2 is a left elevation view of the design shown in FIG. 1;

FIG. 3 is a right elevation view of the design shown in FIG. 1;

FIG. 4 is a front elevation view of the design shown in FIG. 1;

FIG. 5 is a rear elevation view of the design shown in FIG. 1;

FIG. 6 is a top plan view of the design shown in FIG. 1;

FIG. 7 is a bottom plan view of the design shown in FIG. 1;

FIG. 8 is a perspective view of an alternate embodiment of the design shown in FIG. 1, the only distinction being the omission of four ports for selectively dispersing fluid streams, the broken lines showing environment for illustrative purposes only and forming no part of the claimed design;

FIG. 9 is a left elevation view of the design shown in FIG. 8;

FIG. 10 is a right elevation view of the design shown in FIG. 8;

FIG. 11 is a front elevation view of the design shown in FIG. 8;

FIG. 12 is a rear elevation view of the design shown in FIG. 8;

FIG. 13 is a top plan view of the design shown in FIG. 8; and, FIG. 14 is a bottom plan view of the design shown in FIG. 8;
